UNDERGARMENT

William P. Morris, Hobbs, N. Mex.

Application May 2, 1947, Serial No. 745,578

2 Claims. (Cl. 128—159)

1

The present invention relates to undergarments and it consists in the combinations, constructions and arrangements of parts herein described and claimed.

Generally, the invention provides an undergarment having a single piece knit center front and rear portion formed with an elongated vertical opening upon one side which opening is enlarged at its bottom end. To the aforementioned portion a pair of side pieces of broadcloth or the like are adapted to be sewed and a waistband having an elastic insert and an integrally formed fly is adapted to be attached to the upper ends of the aforementioned parts. A single piece reinforcing element, likewise formed of knit material, is adapted to be attached to form a reinforcement for the buttocks and a cover for the vertical opening, at the same time forming a suspensory for the testicles of the wearer.

It is an object of the invention to provide a composite garment which will be seamless at the crotch.

A further object of the invention is the provision of a novel suspensory in a garment of the character described.

Another object of the invention is the provision of a novel fly construction.

A further object of the invention is the provision of a garment of the type above described which will be adaptable to various sized wearers.

A further object of the invention is the provision of an undergarment which will allow great freedom of movement without pulling or chafing the wearer.

Another object of the invention is the provision of a novel closure for the fly of an undergarment.

Other and further objects of the invention will become apparent from a reading of the following specification taken in conjunction with the drawings, in which:

Figure 1 is a front elevational view of an embodiment of the invention.

Figure 2 is a rear elevational view thereof.

Figure 3 is a view similar to Figure 1 with certain parts removed.

Figure 4 is an enlarged sectional view taken along line 4—4 of Figure 1.

Figure 5 is an enlarged sectional view taken along line 5—5 of Figure 1.

Figure 6 is an enlarged sectional view taken along line 6—6 of Figure 1, and

Figures 7 to 11, inclusive, are plan views of elements of the invention.

Referring more particularly to the drawings, there is shown therein an undergarment having

10 a single piece central section 10 which is adapted to form a crotch 11 by folding along the dotted line 12 shown in Figure 7. The section 10 is formed of knit material and, when folded as indicated, will form not only the crotch 11 but a seat and central back portion 13, a right front panel 15 and a left front panel 16. Between the panels 15 and 16 there is provided a vertical opening 17 having an enlarged lower section 18 which extends to a point adjacent the crotch 11.

15 The opening 17 and its enlarged portion 18 have attached therearound by stitching 19 a sweat absorbing member 20. To the sides of the section 10 are attached outer leg portions 21 and 22, preferably formed of broadcloth or the like.

20 A reinforcing member 23, best shown in Figure 9, is adapted to be attached by means of stitching 24 to the section 10 and is provided with a buttocks reinforcing portion 25, a crotch reinforcing portion 26 and a suspensory portion 27. The suspensory portion 27 is provided with a slanted edge 28 which is adapted to be left free of stitching whereby to provide access to the space between the suspensory portion 27 and the remainder of the garment.

25 Referring now to Figure 11, there is provided a waistband 29 having an insert 30 of elastic material and a pair of dependent fly members 31 and 32. Buttons 33 are provided upon the member 31 and buttonholes 34 in the member 32. This assembly is adapted to be attached to the upper portion of the garment by stitching 35.

30 In use, it will be apparent that there is provided a garment which has its central section entirely formed of knit material whereby to provide great elasticity in order that the wearer may have freedom of movement without strain upon the garment.

35 While the garment may be worn by females, it is especially adapted to male wear in that the penis and testicles of the wearer may be inserted through the enlarged opening 18 whereupon the suspensory 27 will act to support these organs. Access to the penis may be readily had through the 40 unstitched edge 28 of the suspensory 27 and the fly 31 and 32 is provided in the usual manner. The sides 21 and 22, being formed of broadcloth or the like will provide coolness in the garment. It will be understood that the identical construction may be utilized with the elongated type of drawers.

45 While but one form of the invention has been shown and described herein, it will be readily apparent to those skilled in the art that many minor modifications may be made without depart-

ing from the spirit of the invention or the scope of the appended claims.

What is claimed is:

1. A garment of the character described comprising a single piece central front and rear section formed of knit material, outer leg sections formed of cloth, a waistband having dependent integrally formed fly sections, an elastic insert in said waistband, said front section having a vertically extending slot provided with an enlarged lower portion and a border of sweat absorbing material affixed to the inner side of the front knit section adjacent the opening therein.

2. A garment of the character described comprising a single piece front and rear section formed of knit material, outer leg sections formed of cloth, a waistband having dependent integrally formed fly sections, an elastic insert in said waistband, a reinforcing patch of knit material formed of a single piece and having a buttocks section, a 20 crotch section and a suspensory section, said last

mentioned section being provided with an opening upon one of its upper sides to provide access to the interior thereof and a border of sweat absorbing material affixed to the inner side of the front knit section adjacent the opening therein.

WILLIAM P. MORRIS.
